UNITED STATES PATENT OFFICE.

WALTER C. REED, OF DALTON, MASSACHUSETTS, ASSIGNOR TO THE TELELECTRIC COMPANY, OF PITTSFIELD, MASSACHUSETTS, A CORPORATION OF MASSACHUSETTS.

CIRCUIT-CONTROLLER.

1,152,843.

Specification of Letters Patent.

Patented Sept. 7, 1915.

Original application filed August 23, 1910, Serial No. 578,587. Divided and this application filed September 11, 1914. Serial No. 861,319.

To all whom it may concern:

Be it known that I, WALTER C. REED, a citizen of the United States, residing at Dalton, in the county of Berkshire and State 5 of Massachusetts, have invented new and useful Improvements in Circuit-Controllers, of which the following is a specification.

In a co-pending application filed on the 23rd day of August, 1910, Serial No. 578,587, 10 I have shown and described an electrically-operated piano player in which provision is made for opening and closing simultaneously a number of branch circuits by means of which the resistance of corresponding 15 playing-magnet circuits is appropriately varied to produce expression effects in the compositions played. For controlling these branch circuits it is important to employ a device which is adapted not only to open 20 or close simultaneously a considerable number of circuits but also to be operated electrically and very quickly, and the subject matter of the present application is a circuit controller having the characteristics just 25 referred to, this application being a division of my aforesaid application Serial No. 578,587.

My circuit controller may have various forms and may be utilized in connection 30 with circuits which are normally either open or closed, and by way of example I have illustrated in the accompanying drawing the preferred construction of my circuit controller when used in connection with circuits which are normally open.

Figure 1 of the drawing shows the controller in vertical section; Fig. 2 is a top plan view of the controller; and Fig. 3 is an elevation of the same as viewed from the 40 right in Fig. 2.

The circuit controller illustrated in the drawing comprises an insulating block 2 mounted on a suitable base 3 and carrying any desired number of spring contact devices, which preferably consist of horizontal spring wires 4 located side by side in proximity to but out of contact with one another. The free end portions of these wires extend over and rest simultaneously upon an insulating support 5 which is movable upward and downward and is pressed upward by a spring 6. The upward pressure

exerted by this spring 6 is opposed to the spring action of the wires 4, so that when these parts are not otherwise acted upon the 55 collective effect of said wires just balances the effect of the spring 6 and the parts remain at rest.

Each of the wires 4 is adapted to move into and out of engagement with a corresponding metallic pin or other contact piece 7 carried by an insulating support 8, and in the particular construction illustrated, in which the controller is normally in open-circuit position, said pins 7 are located below and just out of contact with metallic contact pieces 9 carried by the respective wires 4. Each spring wire 4 and the corresponding pin 7 are connected respectively to circuit wires 10 and 11, which may be included in any circuit which it is desired 70 to open and close by the operation of the controller.

Whenever the support 5 is in the elevated position illustrated all the circuits will evidently be open, but if said support is moved downward against the pressure of the spring 6 all the circuits will be closed at the pins 7 by the spring action of the wires 4. Such movement of the support 5 may be effected 80 in any suitable manner, but preferably, as in the construction illustrated, said support is attached on its under side to the upper ends of soft-iron rods 12 which are arranged to move vertically within the coils 13 of an 85 electro-magnet and form a plunger armature therefor. These rods are normally lifted partially out of the magnet coils by the spring 6, and hence whenever the magnet is energized said rods are drawn into 90 the coils and carry the support 5 with them, thereby causing the various circuits through the wires 4 to be closed as above explained.

It will be observed that the form of circuit controller above described is wholly 95 free from pivotally mounted or sliding parts opposing frictional resistance to its operation, and this fact, as well as the balancing of the spring action on the support for the contact wires, renders the controller sensitive in the sense that a relatively weak current sent through the magnet coils will suffice to operate it very quickly. It is also structurally simple and inexpensive, all of

which characteristics are important in a circuit controller intended to be used in a piano player of the type above referred to.

I claim:

5 1. A circuit controller comprising a series of circuit connections each including an insulated spring wire and a coöperating contact terminal, a support on which the spring wires rest collectively, and a spring acting 10 on said support in opposition to the spring wires and normally balancing the collective effect of the same.

15 2. A circuit controller comprising a series of insulated spring wires each of which is adapted to be connected to one branch of an electric circuit, a corresponding series of insulated metallic terminals adapted to be

connected to the other branches of said circuits respectively and located in position to be engaged by said wires, a support on 20 which the free end portions of the spring wires rest, a spring acting on said support in opposition to said spring wires and normally balancing the collective effect of the latter, and means comprising an electromagnet for moving said support in opposition to the spring acting thereon.

25 In testimony whereof, I have hereunto subscribed my name this ninth day of September, 1914.

WALTER C. REED.
